LUGGAGE CASE

Hugo R. Schwab, Mayville, Wis., assignor to The Peerless Traveling Goods Co., Mayville, Wis.

Application October 19, 1939, Serial No. 300,273

5 Claims. (Cl. 190—41)

This invention relates to improvements in luggage cases.

The primary object of the invention is the provision of a luggage case particularly adapted for the holding of garments, such as ladies' dresses in properly folded position so that they will not become wrinkled or creased while packed.

A further object of this invention is the provision of an improved luggage case which is particularly well adapted for packing long garments, such as ladies' dresses; means being provided therein to permit of the proper initial horizontal positioning of garments so that they may be flat packed and properly folded in a taut and even manner so that there will be no liability of wrinkling or creasing of the garments during transport or while the case is packed.

A further object of this invention is the provision of improved fold providing and maintaining means for a luggage case.

A further object of this invention is the provision of an improved garment supporting and fold providing means for a luggage case.

A further object of this invention is the provision of improved bracket means for luggage cases.

A further object of this invention is the provision of an improved garment hanger for luggage cases.

Other objects and advantages of this invention will be apparent during the course of the following detailed description.

In the drawings, wherein for the purpose of illustration is shown only a preferred embodiment of the invention,

Figure 1 is a plan view of the luggage case, showing the sections open and the parts positioned as they would appear when the garments are folded in the case; no garments being shown in the view.

Figure 2 is a longitudinal sectional view taken through the case in the position shown in Figure 1.

Figure 3 is a view of the opened case, with the body and cover sections in horizontal position, showing the initial position of a garment in the case prior to the initial folding operation.

Figure 4 is a view similar to Figure 3, but showing the initial folding operation.

Figure 5 is a view of the open sections of the case with the garments therein folded and a curtain covering the garments in the cover section.

Figure 6 is a longitudinal sectional view taken through the cover section of the case, with the garments in the relation shown in Figure 5; the

hinged relation of the body section being also shown in this view.

Figure 7 is a perspective view of the case in a display position (without garments).

Figure 8 is a fragmentary view of a bracket construction embodied in the case at the juncture of the cover and body sections; the said sections being shown in closed relation.

Figure 9 is a view similar to Figure 8 but with the sections in right angled or display positioned relation.

Figure 10 is a sectional view taken substantially on the line 10—10 of Figure 9.

Figure 11 is a view of the bracket construction as shown in Figures 8 and 9, but with the body and cover sections in fully opened horizontally positioned relation.

Figure 12 is a view of a hanger associated with the luggage case; the supporting hook thereof being positioned as it would appear when hanging garments on a hook or in a closet.

Figure 13 is a view of the hanger shown in Figure 12, but with the hook in the relation which it assumes when it is associated with the luggage case.

Figure 14 is a vertical sectional view taken substantially on the line 14—14 of Figure 13.

Figure 15 is a view of a spring bracket associated with the free end wall of the cover section of the case, and upon which the garment hangers are adapted to be releasably supported.

In the drawings, wherein similar reference characters designate corresponding parts throughout the several views, the letter A may generally designate the case which includes a body section B and a cover section C. The garment hanger arrangement D is associated with the cover section C and in the case is provided a garment fold producing means E. Bracket constructions F are provided at each side of the case at the hinged juncture of the cover and body sections, and the case has associated therewith a shoe compartment G. The garments adapted to be supported in the case are designated at H in various figures of the drawings.

The body section B consists of side walls 20 and 21, a free end wall 22, an end wall 23 to which the section C is hinged, and a bottom wall 24. The cover section or portion C is of box-shaped formation and includes the side walls 25 and 26; the free end wall 27; end wall 28 to which the section B is hinged, and an outer or top wall 29. The sections B and C are principally hinged at 30, as shown in dotted lines in Figure 1 of the drawings so that they may swing

completely open in the same horizontal plane, as shown in various figures of the drawings, or so that they may be closed. The body section B is provided with a suitable handle 31 and suitable locks or fastener portions 32 of conventional construction may be complementarily provided upon the outer or free end walls 22 and 27 of the sections B and C.

If desired the sections B and C may be of exactly the same size. They are both box-shaped, and while the present invention shows the cover section C as provided with the garment supporting and fold maintaining parts of this invention, the section B may be similarly fitted. That is, either one or the other, or both of them may be provided with the garment supporting and fold maintaining arrangement shown in the drawings and to be subsequently described.

The bracket constructions F are located at each side of the case and connect between the sections B and C. They not only serve to better stabilize the connection of the sections, but enable the sections to be maintained in the so-called "display" position shown in Figure 7, and they further serve as connecting means for one of the garment fold positioning frames as will be subsequently described. Each of these bracket constructions F includes a bracket portion 40 fixedly connected to a side wall of the body section B of the case; a bracket portion 41 fixedly connected to the side wall of the cover portion C of the case, and a connecting link 42 between these portions 40 and 41. As is shown in the drawings, the bracket portion 41 has an attaching ear or flange 45 which is riveted at 46 to the inner surface of each side wall of the cover section of the case, and from there it is bent to provide an attaching flange 47 to which the link 42 is pivotally connected as at 48. The link 42 is of inverted U-shape formation and at its end opposite the pivot connection 48 is provided with a headed retaining pin 50 which slides in a horizontal slot 51 provided in the bracket portion 40 of the bracket construction F. This bracket portion 40 has an elongated body 52 in which the slot 51 is longitudinally provided, and it is provided with attaching ears 53 which are bent out of the plane of the body 52 and receive rivets 54 which attach the bracket portion 40 to the inner surface of each of the side walls of the body section B.

The brackets 40 and 41 are of course located adjacent the hinge connection of the case sections B and C, and as aforesaid the pin 50, which may be a roller, slides in the slot 51 and enables the sections B and C to be properly opened and closed. The body 52 of the bracket portion 40 is provided with a latching notch 57 about midway between the ends of the slot 51 and communicating therewith, and in the lower edge of the slot, into which the slide pin 50 of the link 42 may be engaged, as shown in Figure 9 of the drawings, in order to hold the section B in right angled relation to the body section C of the case. In order to maintain this position a spring urged detent ball 60 is provided upon a leg of the link 42, as shown in Figure 10, maintained in position by a leaf spring 61, and which may engage in a notch 62 of the bracket 40 in order to hold the slide pin 50 of the link in the latch notch 57 and maintain the luggage case sections in the relation shown in Figures 7 and 9 of the drawings. The leaf spring 61 which is socketed to receive the ball 60 preferably is held on the link 42 by means of the headed slide pin 50, as

shown in Figure 10 of the drawings; the head or rivet 65 which is on the slide pin 50 being larger on diameter than the width of the slot 51, for obvious reasons.

When the link 42 has assumed the position shown in Figure 9, of the drawings with the slide pin 50 in its latched position in the notch 57, the spring urged detent ball 60 will of course hold this position until the link 42 is pulled upwardly to detach the slide pin 50 from the notch 57 and place it in the line of the slot 51. When this position is assumed the detent ball 60 will ride just along the top straight edge of the body 52 of the bracket 40, where the stop and guide flange 70 is provided, and the detent in this position, shown in dotted lines in Figure 10 of the drawings, will then prevent the slide pin 50 from dropping into the notch 57, and the case sections B and C may be opened and closed at will between positions where they are in the same plane and their closed position. In order for the pins 50 of these bracket constructions to again enter the notch 57 they must be pushed to force the spring urged detent ball 60 into the position where it is below the straight edge formed by the flange 70 of the bracket 40.

Referring to the garment hanger construction D the same includes a spring bracket construction 80 shown best in Figure 15 of the drawings, adapted to be attached to the free end wall of the cover section C and to receive a considerable number of individual garment hangers 81. The garment hangers 81 are flat and shaped in the usual manner to support the neck and shoulders of a garment and each is provided with a hook-shaped member 84 pivoted at 85 so that the hook end of the member may be pivoted to an upright position as shown in Figure 12 for hanging on the hooks in closets, or collapsed to the position shown in Figure 13. At the opposite side of the pivot from the hook of the member 84 is an extension 86 slotted at 87. This extension 86 projects from the top edge of the hanger portion 81 when the hook end is collapsed as shown in Figure 13 and the slot 87 is in position to be slipped upon the bracket construction 80.

The bracket construction 80 includes a plate portion 89 adapted to be attached as by riveting through openings 90 to the inner surface of the free end wall of the cover section C. Longitudinally, the attaching plate 89 is stamped to provide a socketed portion 91; the socket opening downwardly and adapted to receive the end 92 of the spring arm 93. As shown in the drawings the bight portion 94 which connects the portion 92 and the spring arm 93 engaged against the inner surface of the bottom wall at the juncture of the bottom and end walls of the case section B and this holds the portion 92 in the socket 91. The spring arm 93 extends diagonally upward and is bowed at 95 to engage against the top inclined end 96 of the attaching plate 89. From this position the free end of the spring arm 93 may be flexed to insert the same in the slot 87 of the garment hanger and any number of the latter may be thus positioned upon the spring arm 93, from which they may be individually detached as desired. The dotted lines in Figures 3 and 4 of the drawings show the assembly of a large number of these flat garment hangers in position upon the spring arm of the bracket construction 80.

Referring to the garment fold forming arrangement the same includes a primary fold producing frame or member 160 and a second-

ary fold producing frame or member 101. The former consists of side arms 102 and 103 pivoted at 104 on the inner surfaces of the side walls 25 and 26 of the cover section C above the midway point of each of said walls. The arms 102 and 103 have offset feet where they are pivoted and at their free ends they support a fold producing and maintaining roller 106 which may be of any approved construction. These arms are sufficiently long that the roller 106 may be positioned entirely inside of the cover compartment of the cover section C and spaced from the end wall 28 thereof when it is in its fold producing position; the space between the end wall 28 and the roller 106 in this position as shown in Figures 1 and 2 of the drawings being sufficient to accommodate the thickness of the number of garments which it is intended to maintain in the case. Figure 4 illustrates the operation of the frame or member 100 to facilitate initial folding of the garments, as will be subsequently described.

The garment fold maintaining arrangement further includes the frame 101 above mentioned. This includes side arms 110 and 111 which are pivoted to the brackets 41 above described, at pivot points 113, as shown in Figures 8, 9 and 10 of the drawings, and elsewhere. The arms 110 and 111 at their pivot ends are disposed at an obtuse angle with respect to the line of the remaining portions of the arms, so that these arms 110 and 111 may lie in a horizontal position over the open end of the body section B of the case preparatory to folding of garments, as shown in Figure 3 of the drawings. At their free ends the arms 110 and 111 are provided with a fold supporting bar or rod 120. These arms 110 and 111 as to length, and the positions of the bar 120 are of such dimensions that the entire frame 101 may be disposed in the compartment of the cover section C, as shown in Figure 2 of the drawings.

It was before mentioned that inturned horizontal flanges 70 were provided upon the top edge of the brackets 40, as shown in Figure 10 of the drawings. These flanges serve to support the arms 110 and 111 of the fold frame 101 in a horizontal position, as shown in Figure 3 of the drawings, so that the bar 120, while positioned as it is in Figure 3 of the drawings, will serve to maintain the garments in flat horizontal position and prevent their sagging into the compartment of the case section B. It should be noted that the fold bar 120 is positioned inwardly a slight distance from the ends of the arms 110 and 111; these extensions beyond the bar 120 serving to hold the sides of the thickness of garments in position.

From the foregoing description the method of folding the garments and properly positioning them in the luggage case will be apparent. The sections B and C are opened to the position shown in Figure 3 with the fold frames 100 and 101 also in the position shown in Figure 3. Of course, prior to that the garments were assembled upon the hangers 31 and positioned in bulked relation shown in Figure 3. The first step of folding is to swing the frame 100 to the position shown in Figure 4 and the fold bar 106 will then position the garments for the initial fold. The frame 101 is then swung as shown in Figure 4 and moved to the position shown in Figure 6 and this places the garments in three layers, and with two folds; the fold points of course being at the rollers 106 and 120. It is to

be noted that the entire folded assemblage of garments is within the compartment of the cover section C.

The next operation is that of strapping the folded garments and their frames in position. To that end the straps 126 and 127 are connected on the inner surfaces of the opposite side walls of the cover section C and they are provided with suitable buckle means 128 well known in the art, to effect their connection. They are placed close to the free end of the cover section C.

A curtain 130 is connected to the hinged end of the cover section C and of a length and width 15 to completely cover the assemblage of garments packed within the cover section C. The curtain may be of any approved nature and may include a slat reinforced free edge 131. The inner surface of the free end wall 27 of the cover section C is provided with suitable fastener portions 135 adapted to cooperate with complementary fastener portions 136 which are adjustably provided on pull straps 137 at the free end of the curtain, in order to hold the closed position of the curtain over the packed garments, as shown in Figure 6 of the drawings.

As above stated the body section B of the case may be provided with means similar to that above described for packing garments. In lieu thereof it may be provided with other accessories. One of these accessories may be the improved shoe compartment G, which is flexible in nature and pocketed at the hinged end of the section B; the same consisting of flexible top and bottom panels 140 and end panels; the top panel being connected by a sliding "zipper" 150 so that the pocket may be opened or closed. The dotted lines shown at 151 in Figure 5 of the drawings designate the open position of the top panel of the shoe compartment.

From the foregoing description of this invention it will be apparent that an improved luggage case has been provided which is relatively simple, and one in which the bulk arrangement of garments may be folded and packed without liability of becoming wrinkled or creased. The method of packing is simple and improved and there is no complicated mechanism which cannot be readily understood by anyone.

Various changes in the shape, size, and arrangement of parts and rearrangement of the steps of packing may be made provided said changes come within the scope of the claims.

I claim:

1. In a luggage case the combination of a cover section, a body section, garment hanger means at an end wall of at least one of said sections, a frame on said sections including pivoted side arms and a fold maintaining bar adapted to be swung to a fold maintaining position to a point adjacent the wall opposite that wall which supports the garment hangers, said side arms being pivoted on an axis transverse to the section on which mounted so that the bar thereof may be swung to a position entirely out of obstructing relation with the compartment of said case section, and a second fold frame independently pivoted on the case with respect to the first frame and adjacent that wall which is opposite the wall on which the garment hanger is connected and having a fold bar at its free end adapted to assume a position adjacent to the garment hanger wall of the case section when in garment fold maintaining position.

2. A luggage case comprising a pair of movably

connected sections which when opened lie in the same general plane, one of such sections at its free end having means for hanging a garment thereon so that the garment initially may be laid in extended relation upon both of said sections when the latter are open, a fold producing member pivotally mounted upon that section to which the garment hanger is connected on a transverse axis remote from the point of connection of said sections and adapted to be moved into position to hold a garment hung on the hanger adjacent the point of connection of said sections so that the garment may be folded at that location upon itself, and a second fold producing member connected with that section to which the first fold producing member is connected and independent of the first fold member and positioned so that the garment when it is first laid in extended relation over the sections will lie over the second fold member, said second fold producing member, when the case sections are opened, having its fold producing portion located remote from the connection of said sections whereby, after the first fold producing member is in position for producing a fold in the garment, the second fold producing member may be moved to place the garment in a folded relation upon itself in the first mentioned case section and produce a second fold in the garment adjacent the garment hanging means of the first mentioned case section.

3. In a luggage case, the combination of a pair of connected box sections, means at the free end of one of said sections for hanging a garment thereon, a fold producing member pivotally connected adjacent to the connection of said sections extensible into and out of the section which supports said hanger and having a fold bar positioned adjacent to said hanger when said fold producing member is disposed within said section, and a second fold producing member pivotally mounted upon that section upon which the hanger is mounted at a location close to the central portion of said section and swingable into and out of said section and having a fold bar positioned adjacent to the point of connection of

said sections when the second mentioned fold producing member is disposed within the section on which it is mounted.

4. In a luggage case, a combination of case sections, one of said sections having a fold producing member pivoted adjacent to an end wall thereof and extensible into and out of said section and having a fold producing bar adapted to lie adjacent to the opposite end wall of said section 10 when it lies within the section, and a second fold producing member pivoted directly to the same section and independently of the first mentioned fold producing member at substantially the midway point between the end walls above mentioned, 15 and extensible into and out of said section and having a fold bar adapted to lie within the section adjacent to that end wall to which the first mentioned fold producing member is closest with respect to its pivot connection.
5. In a luggage case, the combination of luggage case sections including end and side walls, one of said sections having a fold producing member pivoted thereto adjacent to an end wall and having a fold bar adapted to lie adjacent to the opposite end wall of said section when the fold producing member is disposed within said section, and a second fold producing member pivoted within the same section to which the first mentioned fold producing member is pivoted and 20 at a location about midway between the end walls of said section but closer to the end wall remote from that end wall adjacent to which the first mentioned fold producing member is pivoted, the second mentioned fold producing member having a fold bar adapted to lie adjacent to that end wall closest to the pivot of the first mentioned fold producing member when the said second fold producing member is disposed within said section, the fold bar of the second fold producing member 25 adapted to lie upon the top edge of the wall of its section which is closest to its pivot mounting when said second fold producing member is extended out of the section.

HUGO R. SCHWAB.
